UNITED STATES PATENT OFFICE

160,435

TEXTILE FABRIC OR SIMILAR FLAT
SURFACE MATERIAL

Eugene Seeley, New York, N. Y., assignor to Fall
River Curtain Co., Inc., New York, N. Y., a cor-
poration of Massachusetts

Application January 26, 1949, Serial No. 515

Term of patent 3½ years

(Cl. D92—1)

To all whom it may concern:

Be it known that I, Eugene Seeley, a citizen of the United States, residing in the Borough of Manhattan, city, county, and State of New York, have invented a new, original, and ornamental Design for a Textile Fabric or Similar Flat Surface Material, of which the following is a specification, reference being had to the accompanying drawing, forming part thereof.

On the drawing, the figure is a plan view of a piece of textile fabric or similar flat surface material, showing my new design. A design unit is shown in full lines, and is repeated as indicated by the extensions beyond the broken line boundary of the design unit.

I claim:

The ornamental design for a textile fabric or similar flat surface material, substantially as shown and described.

EUGENE SEELEY.
